PLUMBING FIXTURE

Paul W. Leffland, Dallas, Tex.

Application September 24, 1934, Serial No. 745,234

18 Claims. (Cl. 4—4)

This invention relates to new and useful improvements in plumbing fixtures.

One object of the invention is to provide an improved plumbing fixture which includes a bath tub and a lavatory integrally constructed, whereby a single unit is produced.

An important object of the invention is to combine a bath tub with a lavatory so as to form a single fixture, whereby common water supply lines to both fixtures, as well as a common drain, may be employed; thereby reducing the cost of installation and the necessary labor to a minimum.

Another object of the invention is to construct a bath tub integral with a lavatory so as to provide a single fixture; the lavatory being disposed over a portion of the tub, whereby the combination fixture will cover no more floor space than the tub itself, the disposition of the lavatory being such as not to reduce the interior space of said tub.

A further object of the invention is to provide an improved bath room fixture including a bath tub and a lavatory integrally constructed, and having a common drain and trap for both tub and lavatory, with independently operated drain plugs, whereby the tub or lavatory, comprising a single unit, may be used separately.

Still another object of the invention is to provide a single improved bath room fixture comprising a bath tub and lavatory, which is so constructed as to require a minimum quantity of piping, vents, drains and traps, and which is arranged so that the installation may be accomplished with a reduction in cost and labor; the fixture being arranged to permit ready access to the piping, for inspection, at all times after installation.

A still further object of the invention is to construct a bath tub and a lavatory as a single unit, thereby not only reducing the original cost and lessening the labor and time necessary for manufacture, but also eliminating the necessity of making two separate fixtures, as is the usual practice.

A typical example of my invention is illustrated and described herein, and the claims hereinafter appended set forth the novelty inherent in my invention.

50 In the accompanying drawings:

Figure 1 is a plan view of a plumbing fixture constructed in accordance with the invention,

Figure 2 is a side elevation of the same,

Figure 3 is a longitudinal vertical sectional view, taken on the line 3—3 of Figure 1,

Figure 4 is a transverse vertical sectional view, taken on the line 4—4 of Figure 1,

Figure 5 is a transverse vertical sectional view, taken on the line 5—5 of Figure 1;

Figure 6 is an enlarged sectional view, taken on the line 6—6 of Figure 1, with parts of the drain pipe in section,

Figure 7 is an enlarged detail showing the water supply pipes to both the tub and lavatory,

Figure 8 is a sectional detail, showing the operating cables for the drain plugs or stoppers,

Figure 8a is a sectional detail showing the drain plug of the tub and its operating means,

Figure 9 is a floor plan of a bath room, showing the fixture installed therein,

Figure 10 is a plan view of a slight variation of the invention,

Figure 11 is a plan view of still another form of the invention, and

Figure 12 is a vertical sectional view, taken on the line 12—12 of Figure 11.

In the drawings the numeral 10 designates a bath tub which may be of any desired size. The tub is preferably constructed of metal, or other suitable material, and is supported on legs 11. 25 One end wall 12 of the tub may be sloped in the usual way, while the other end wall 13 extends a short distance from the bottom of the tub and is then inclined inwardly and upwardly. This end is then extended vertically to form a wall 14, 30 which is positioned above the top of the tub, as is clearly shown in Figures 2 and 3.

A lavatory or wash basin 15 is disposed over the inclined wall 13 of the tub and is adjacent the wall 14, being made integral therewith. This 35 basin is preferably of the same material as the tub and in manufacturing it is obvious that the tub and basin may be cast in one piece, thereby greatly reducing labor and material costs. The integral construction of the lavatory with the 40 tub, as well as the disposition of said lavatory over the end of the same, provide a single unit which covers no more floor space than the tub by itself. This permits installation of a single unit which has both fixtures, in a space formerly 45 necessary for one.

The lavatory is positioned a sufficient distance above the inclined end 13 of the tub to provide a space 16 therebetween. The tub 10 is, of course, provided with the usual cold and hot water control valves 17 and 17', which are mounted in the wall 14. The lavatory 15 has the usual cold and hot water faucets 18 and 18' mounted on the top thereof.

An important feature of the invention is the 55

single source of supply for the cold water to both fixtures, and a single source of supply for the hot water to both fixtures. The supply lines are shown in detail in Figure 7. The cold water 5 is conducted from a suitable source of supply through an inlet pipe 19 to a T 20. A pipe 21 leads from one side of this T to the tub faucet 22. The cold water control valve 17 is connected in the pipe 21 and it is obvious that this valve 10 controls the flow of cold water to the tub faucet 22. The other side of the T 20 is directly connected by a pipe 24 to the cold water faucet 18 of the lavatory, whereby cold water is supplied thereto from the main supply line 19. If desired, a short lead pipe 21' connects the pipes 21 and 27 with a spray head 23, whereby hot or cold water, as desired, may be conducted to said head. A cut-off valve 23' is connected in the line 21'.

20 Hot water is conducted from a suitable source of supply through an inlet pipe 25 to a T connection 26. A lead-in pipe 27 connects one side of this T with the tub faucet 22 and the hot water control valve 17' is connected in this pipe 25 27, whereby the hot water supply to the tub is controlled. The other side of the T is directly connected through a pipe 28 with the hot water faucet 18' of the lavatory. Thus, it is obvious that by constructing the tub and lavatory as a 30 single unit, it is possible to use single supply lines for the hot and cold water to both fixtures, thereby not only providing for easier and quicker installation, but also greatly reducing the cost of the necessary piping.

35 If desired, an opening 29 may be provided in the wall 14 (Figure 7) and this opening is normally covered by a panel 30, which when removed will give easy access to the water control valves for the tub, as well as to the various 40 pipe connections. This makes for ready and easy inspection at all times after installation.

The tub 10 is provided with the usual drain 31 which is normally closed by the usual type drain plug or stopper 32. The tub also has the 45 usual overflow drain opening 33 in the inclined wall 13. The lavatory is also provided with a drain 34 normally closed by a plug or stopper 35. The usual overflow 36 is provided near the top of the basin of said lavatory. Connected with 50 the drains of both the tub and lavatory, a single drain pipe 37 is provided. This pipe, as clearly shown in Figure 6, is preferably made an integral part of the tub and lavatory and not only serves to conduct the water from the drains but 55 also serves to support the outer end of the lavatory, thereby making for a more substantial structure.

The lower end of the drain pipe 37 is connected to a trap 38 of the usual construction, and 60 a vent pipe 39 preferably mounted in the wall 65 of the room is connected therewith. From the foregoing, it is obvious that the tub and lavatory not only are supplied with cold and hot water by a common supply for each, but a single drain pipe, trap and vent are all that is necessary. This eliminates using a double drain and double trap, as is the usual practice, for the two fixtures when they are made separately. The reduction of cost, as well as minimizing the labor, 70 is obvious.

75 For independently operating the drain plugs 32 and 35 so that the tub and lavatory may be drained separately, a hand wheel 40 is provided in panel 30 of the wall 14 for the plug 32 of the tub and a similar wheel 41 is provided on the

lavatory between the hot and cold water faucets 18 and 18' for controlling the plug 35. The hand wheel 40 is mounted between the control valves 17 and 17' in the panel 30 of said wall and is secured to the outer end of a rotatable shaft 42 8 journaled in said wall and in lug 43. The inner end of the shaft carries a small pulley 44 which has a cable 45 secured thereto. The cable passes downwardly through the space 16 between the lavatory and the inclined wall 13 of the tub, 10 around idler pulleys 46 and 46', and has its lower end fastened to a pivoted arm 47. The outer end of this arm carries a bearing cup 48 which is in constant engagement with the lower end of the drain plug 32. It is obvious that when 15 the hand wheel 40 is rotated the cable 45 is wound on the pulley 44 and the pivoted arm 47 is swung to raise the plug 32 and permit escape of water from the tub. When the wheel is rotated in an opposite direction, the cable is unwound from the 20 pulley 44 and the weight of the plug 32 causes the same to drop into the drain opening 31 to close the same.

The operation of the lavatory drain plug 35 is accomplished in a similar way. The hand wheel 25 41 is secured on the upper end of a rotatable shaft 49 which carries a pulley 50 at its lower end. A cable 51 has one end secured to the pulley 50 and its other end fastened to the vertical arm of of a bell crank lever 52. The horizontal arm of 30 the lever carries a bearing cup 53 which is in constant engagement with the lower end of the drain plug 35. It will be seen that rotation of the wheel 41 will wind the cable 51 on the pulley 50 which will swing the lever 52 to raise the plug 35 35 and permit water to drain from the lavatory basin.

A recess 54 is provided in the exterior wall of the fixture below the lavatory, as shown in Figure 5, to more comfortably accommodate the 40 feet of the user.

From the foregoing, it is obvious that a single plumbing fixture, which combines two necessary fixtures, is provided. The advantages are many. The floor space necessary for my improved fixture is only that necessary for the ordinary tub. The manufacturing of two separate fixtures is eliminated, which permits construction at a minimum of cost and labor. The quantity of piping, drains and traps is reduced, thereby decreasing 45 cost and making for easier installation. A complete and compact, as well as a sturdy and attractive unit, without sacrificing efficiency or convenience, is produced.

The unit may be mounted in a bath room, as 55 shown in Figure 9, and will permit said room to be made smaller than usual without reducing the necessary usable space. The unit may be secured on three sides as shown in dotted lines in Figure 1, or it may be fastened on only two sides as 60 shown in Figure 10. In the latter case, the user may stand at the end when using the lavatory.

In Figures 11 and 12, I have shown another form, wherein the unit is constructed as square in shape. The parts thereof are similar to the 65 form described and a description is unnecessary. It is pointed out that the unit may be made of any shape or size suitable for the room in which it is to be positioned. The particular method of constructing the unit is unimportant, as it may 70 be cast in one piece of metal or it may be made of pressed metal.

I claim:

1. In a plumbing fixture, the combination of a bath tub, a lavatory mounted above and over- 75

hanging said tub, a common source of water supply to both the tub and lavatory, independently operated faucets in said tub and said lavatory connected with said common source of supply, 5 and a removable panel covering the faucets, whereby access to the faucet connections may be had at all times.

2. In a plumbing fixture, the combination of a bath tub, and a lavatory disposed over said tub and integral therewith, and a recess in the exterior wall of the tub at the base thereof for accommodating the feet of the user of said lavatory.

3. In a plumbing fixture, the combination of 15 a bath tub, a lavatory mounted above and overhanging said tub, the tub having a recess in its outside wall below said lavatory for accommodating the feet of the user of the lavatory, an enclosed compartment between lavatory and tub, 20 means within said compartment for independently operating drain plugs for releasing the water from the tub and lavatory separately of each other, and controls for said operating means disposed upon the wall of said compartment.

25 4. In a plumbing fixture, the combination of a bath tub, a lavatory mounted above and overhanging said tub, a wall between the tub and lavatory for covering water pipes, and a removable panel in said wall, whereby access to said pipes may be conveniently had.

5. In a plumbing fixture, the combination of a bath tub, a lavatory mounted above and overhanging said tub, a wall between the tub and lavatory for covering water pipes, a removable 35 panel in said wall, whereby access to said pipes may be conveniently had, and water supply controls disposed on said panel above the usable tub space, for the convenience of the bather.

6. In a plumbing fixture, the combination of a 40 bath tub, a lavatory mounted above and overhanging said tub, an inside wall of the bath tub extending upwardly and toward the center of the bath tub to cover a portion of the usable tub space, water supply controls mounted on said upwardly extending wall, near the center of the tub, for the convenience of the bather.

7. In a plumbing fixture, the combination of a bath tub, a lavatory mounted above and overhanging said tub, an upwardly extending wall of 50 the bath tub in proximity to the lavatory and made integral therewith, said wall extension constituting support for the lavatory, and a removable panel in said wall, for covering water pipes, whereby ready access to the pipes may be had.

55 8. In a plumbing fixture, the combination of a bath tub, a lavatory mounted above and overhanging said tub, a wall between the tub and lavatory for covering water pipes, and a removable panel in said wall, whereby access to water pipes may be conveniently had, said panel being secured in place by a water faucet control.

9. In a plumbing fixture, the combination of a bath tub, a lavatory mounted above and overhanging said tub, a housing beneath the lavatory 65 and substantially above a portion of the usable tub space, whereby pipes may be housed and enclosed, and a removable panel upon the wall of said housing, whereby access to pipe connections may be had at all times, said housing wall being of integral construction with the tub and lavatory and forming a support for the lavatory.

10. In a plumbing fixture, the combination of a bath tub, a lavatory mounted above and overhanging said tub, a housing wall enclosing a 75 space disposed between the lavatory and usable

tub space, an extension of said housing wall in a substantially vertical position above usable tub space and towards the center thereof, and water supply controls mounted upon said wall extension, for convenience of the bather standing or sitting. 5

11. In a plumbing fixture, the combination of a bath tub, a lavatory mounted above and overhanging said tub, a housing enclosing a space disposed between the lavatory and usable tub space, an extension of the wall of said housing in a substantially vertical position above usable tub space and towards the center thereof, water supply controls mounted upon said wall extension, for convenience of the bather standing or sitting, means on said wall extension for winding a cable, and a cable extending from said winding means, through the housing space, and connecting to a drain plug in the bath tub, whereby the drain plug may be operated to allow the escape of water. 15

12. In a plumbing fixture, the combination of a bath tub, a lavatory mounted substantially above said tub, a drain plug comprising a stopper mounted on the upper end of a slidible rod, having a spherical base on its lower end, a fixed support for said rod, a lever fixed at one end and having a concave seat on its opposite end to receive the said spherical base and articulate therewith, and cable control means for elevating said lever whereby the stopper may be raised to allow 20 escape of water. 25

13. In a plumbing fixture, the combination of a bath tub, and a lavatory mounted above and overhanging said tub, said tub having a recess in its interior side below said lavatory for accommodating the feet of the user of said tub, and a recess in the exterior wall of the tub at the base thereof for accommodating the feet of the user of said lavatory, water supply controls disposed above the usable tub space, and means for 30 so supporting said controls. 35

14. In a plumbing fixture, the combination of a bath tub, and a lavatory mounted above and overhanging said tub, said tub having a recess in its interior side below said lavatory for accommodating the feet of the user of said tub, and a recess in the exterior wall of the tub at the base thereof for accommodating the feet of the user of said lavatory, water supply controls disposed above the usable tub space, means for so supporting said 40 controls, and a housing enclosing a space beneath the lavatory and above the usable tub space, wherein water supply pipes may be disposed. 45

15. In a plumbing fixture, the combination of a bath tub, a lavatory mounted above and overhanging said tub, the tub having a recess in its interior side below said lavatory for accommodating the feet of the user of said tub, water supply controls disposed above the usable tub space, and means for so supporting said controls. 50

16. In a plumbing fixture, the combination of a bath tub, a lavatory mounted above and overhanging said tub, the tub having a recess in its interior side below said lavatory for accommodating the feet of the user of said tub, water supply controls disposed above the usable tub space, means for so supporting said controls, and a housing between lavatory and tub, whereby water supply pipes may be enclosed. 55

17. In a plumbing fixture, the combination of a bath tub, a lavatory disposed over said tub and integral therewith, an end wall of said tub extending inwardly and upwardly above the usable tub space and terminating in a substantially vertical panel across said tub near the center there- 70 75

of, water supply controls on said panel presented substantially toward the center of the tub, to afford ready and convenient operation by the bather.

5 18. In a plumbing fixture, the combination of a bathtub, and a lavatory disposed over said tub, a wall below said lavatory and above usable tub

space, a removable panel in said wall, whereby access to pipes may be had, and an exterior rim of the lavatory and an exterior wall of the tub disposed in substantially vertical and parallel separate planes to provide accommodation for the 5 feet of the user of said lavatory.

PAUL W. LEFFLAND.
